UNITED STATES PATENT OFFICE.

MARCO ANTHONY STELLA, OF CHICAGO, ILLINOIS.

AWNNG.

Application filed October 28, 1921. Serial No. 511,123.

It is the object of my invention to provide a new and useful awning for buildings and the like so designed as to protect all the parts within a closed housing when the awning is not in use.

It is a further object to provide means for raising or lowering the awning from the interior of the building.

It is the further object to provide new and improved means for raising the awning.

It is the further object to provide an awning having end portions with means for drawing or rolling up the end portions and paying out contemporaneously with the movement of the main portion of the awning.

The above and other features of novelty, advantages and capabilities will become apparent from a detailed description of the accompanying drawings, in which I have illustrated an awning and operating means embodying one form of my invention, but the construction there shown is to be understood as illustrative only and not as defining the limits of my invention.

Fig. 1 is a vertical sectional view of a device embodying one form of my invention showing it applied to a window.

Fig. 2 is a front elevational view of the same showing the housing for the awning in section.

Fig. 3 is a front elevational view showing the awning closed and all the parts encased within the housing.

Fig. 4 is an enlarged vertical sectional detailed end view partly in section of the same showing the awning down or in open position.

Fig. 5 is a detailed view of the driving connections for drawing up and paying out the awning.

Fig. 6 is an enlarged detailed view of the gear connection between the main roller and the end rollers.

Fig. 7 is an enlarged detailed view of the swinging end frame member of the awning and its connecting parts.

Fig. 8 is a plan view of the same, showing the front frame member in section.

Fig. 9 is a sectional view taken on the line 9—9 of Fig. 7.

Fig. 10 is a sectional view taken on the line 10—10 of Fig. 7.

Fig. 11 is a detailed perspective view of the sliding trip designed to travel in the swinging end members.

Fig. 12 is an end elevational view showing the parts in closed position within the housing, the latter being in section.

Fig. 13 is an enlarged elevational view of the awning in closed position within the housing with the strip on the frame member, for closing the opening in the housing removed, and

Fig. 14 is a sectional view of the housing taken on a line 14—14 of Fig. 13.

Referring to the drawings in detail, the housing 9 is constructed of sheet metal and comprises a main portion and two legs fixed to the building in any suitable manner. The main roller 10 on which the main portion 11 of the awning is taken up and paid out, is mounted within the main portion of the housing and is provided on each end with a spindle 12, which spindles are rotatably mounted on suitable brackets 13 and 14 fixed to the window frame or building adjacent to the window within the housing by suitable bolts or screws. The spindle on the right of the structure, as illustrated in the drawings, has rigidly fixed thereto a driving gear 15 which is in mesh with the gear 16, mounted on the shaft 17, which shaft is rotatably mounted in the brackets 13 and 18, both of which are rigidly fixed to the building. The shaft 17 at its opposite end is provided with a beveled gear 19 in mesh with the gear 20 on the shaft 21, which shaft extends through the building as best shown in Fig. 1, and is suitably connected with a reversible electric motor on the interior of the building for driving the same in either direction.

The main portion or front of the awning, which, of course, is made of the usual flexible material, is connected at its free end to the front frame member 22 to which there is connected near each end thereof side members 23. Said side members in the modification shown being constructed of a hollow slotted tube suitably connected to the collars 24 which collars are in turn rigidly fixed to the front frame member 22 by any suitable means, as best shown on Figures 7 and 8. The opposite or inner ends of said side members 23 is pivotally connected as best shown in Figs. 6 and 7, to bifurcated brackets 25 which brackets are in turn rigidly fixed to the window frame or building.

From the description thus far it will be seen that when the motor within the building is operated in the proper direction the main roller 10 is driven in a manner to wind

thereon the main portion of the awning, which in turn draws up the front frame member and swings the outer end of the side members upwardly in the path of an arc; 5 while this operation is taking place I have provided means for winding up the ends or side portions of the awning which I will now describe.

Mounted within each vertical leg of the 10 housing 9 is a side roller 26 on which the side portions of the awning are wound for taking up and paying out. These rollers are rotatably mounted in the brackets 25 and 27 which are fixed within the housing to the 15 window frame or building. The upper end of the roller is provided with a spindle on which there is slidably mounted a beveled pinion 28 which pinion is adapted to move into and out of mesh with a comparatively 20 large beveled gear 29, mounted on the spindle 12 of the main roller. In the particular instance shown the ratio is about two to one, that is, the gear 29 has about twice the diameter of the pinion 28, so that the side rollers 25 travel about one half as fast as the main roller 10. The lower outer free end of the 25 side portions of the awning are secured by any suitable means to a sliding bracket 30 slidably mounted in the longitudinal slot in the side members 23, which members are 30 inferiorly provided with a comparatively small slotted tube 31 secured by means of screws or the like to the lower side of the members 23,—the brackets 30 being provided 35 with upper and lower flanges 32 and 33, the upper one being adapted to engage the inner surface of the frame members 23 and the lower flange to ride or rest on the small tube 31 as best shown in Fig. 10. These brackets 40 have a downwardly extending portion 34 to which are attached flexible cords or the like 35. The opposite end of each cord is wound on a roller or shaft 35^a rotatably mounted by any suitable means in a suitable bore in each end of the front frame member 22. These rollers or shafts are 45 provided with suitable coiled spring motors 36 for driving such shafts in an anti-clockwise direction for the purpose of unrolling or paying out the side portions of the awning as the awning is lowered. These 50 slideable brackets 30 serve an additional function for when they reach their limit of inward-movement the pins 37 carried thereby engage the bell crank levers 38 which are pivoted on the brackets 25 as best shown in Figs. 7 and 8 and move the upper arm of the lever inwardly thus pulling down on the links or rods 39. The rods or links 39 are each provided 55 at the upper ends with a head 40, which head is integrally provided with bifurcated fingers 41, the hub 42 is rotatably but non-slidably connected with the fingers 41 in any suitable manner, such for example, as the 60 well known pin and groove connection best

shown in Figs. 5 and 6. As a result of this arrangement the downward movement of the link 39 moves the pinion 28 out of mesh with the large gear 29 and prevents further winding up of the side portion of the awning although the winding operation of the main portion of the awning will continue until it is completely wound and the frame members drawn into place within the housing. 75

Working or pulling against the free end of the side portion of the awning at all times are the coiled spring motors 36 in the front frame member 22, so that as soon as the lowering operation of the awning is started these coiled spring motors pull the sliding brackets out of engagement with the bell crank levers 38 whereupon the compression springs 43 mounted around the links or rods 39 and between the heads 40 and brackets 27^a cause the heads 40 to move upwardly throwing the small pinion 28 in to mesh with gear 29, after which the side portions of the awning cannot be paid out faster than is permitted by the travel of the motor. 90

It will thus be seen that I have provided new, efficient and novel means for winding up and paying out the side portions of the awning contemporaneously with the main portion; that all the parts are driven from the interior of the building and that the means for drawing up and paying out the side portions of the awning are automatically engaged and disengaged. 95

The entire mechanism including the awning, front frame members and side frame members are, when in close position, drawn within the sheet metal housing 9, which housing is rigidly fixed to the building or window frame and comprises side members, a top member with a sufficiently large slot or opening to allow such parts to pass in and out, which opening or slot is best illustrated in Fig. 13 and is preferably provided with counter sunk edges as there shown. 105

In order to fully protect the awning and parts thereof after having been drawn within the housing, it is necessary to close the slot or opening. This I accomplish by securing to the front frame members and the side frame members a closure or strip of metal 45 of the desired size to overlap the opening in the housing proper, but to fit within the counter sunk edges so that the outer surface of the housing will be flush when the parts are in proper position. This closure or strip is indicated by the reference 45 as best shown in Figs. 1, 3, 4, 6, 8 and 13. The strip is secured directly to the front frame member by any suitable means, such as screws, nails and the like and to the side members by means of sheet metal brackets 46 as best shown in Figs. 4 and 9, 115 120 125 130

so that the strips of the side members are in alignment with the strip or closure on the front frame members.

5 While I have shown the shaft for raising and lowering the awning driven by an electric motor, it can also be raised or lowered by means of a shaft running down near the floor and operated by a crank having a pinion in mesh with a pinion on such shaft.

10 Having thus described my invention, I claim:

1. In an awning, the combination of a main roller, side rollers, a swinging awning frame comprising front and side members, 15 a flexible awning attached at one end to said frame and adapted to be wound on said rollers and means adapted to automatically disconnect the side rollers from the main rollers before the main portion of the awning has reached its closed position of rest.

2. In an awning, the combination of a main roller, side rollers, a swinging awning frame comprising front and side members, a flexible awning attached at one end to 25 said frame and wound on said rollers, means for driving said main roller, driving connections between said main roller and said side rollers and slidable means carried by the side members of said awning frame 30 adapted to automatically disconnect said side rollers from the main roller before the main portion of the awning has reached its closed position of rest.

3. In an awning, the combination of a main roller, side rollers, a swinging awning frame comprising front and side members, 35 a flexible awning attached at one end to said frame and wound on said rollers, means adapted to be operatively connected for driving said main roller and adapted to be operated from the interior of the building, driving connections between said main rollers and said side rollers and slidable means carried by the side members of said 40 awning frame adapted to automatically disconnect said side rollers from the main roller before the main portion of the awning has reached its closed position of rest, and means carried by the front frame member of said 45 awning for pulling out the side portions of said awning contemporaneously with the downward movement of the main portion.

50 4. In an awning, the combination of a swinging frame comprising front and side members adapted to be pivotally mounted

on a building, a main roller, side rollers, a flexible awning connected at one end with the main portion of said frame and at its opposite end to the main roller, side awning members wound at one end on said side 60 rollers and connected at their opposite end to a sliding member slidably mounted in the side frame members, and a spring motor mounted on the front frame member, operatively connected to said slideable member, 65 substantially as and for the purpose set forth.

5. In an awning the combination of a swinging frame comprising a front and side frame members, brackets pivotally connected 70 to said side frame members, said brackets being adapted to be fixed to a building, a main roller, side rollers, a main awning operatively connected at one end to said main roller and at its opposite end to the 75 front frame member, side awnings, operatively connected at one end to said side rollers and at the opposite end to a slideable member, slidably mounted in said side frame members, driving connections between said 80 main roller and side rollers, bell crank levers pivotally mounted on said brackets and operatively connected to said driving connections in such a manner as to make and break said connection upon the operation of 85 said bell crank levers, a pin carried by said slideable members and adapted to engage said bell crank levers for throwing the side rollers out of driving connection with the main roller and means 90 for automatically making such connection on the initial downward movement of the awning substantially as and for the purpose set forth.

6. In an awning, the combination of a 95 main roller, side rollers, a swinging awning frame, comprising front and side members, flexible awnings attached to said frame and roller means for normally driving the side rollers with the main roller and means for 100 automatically disconnecting the side rollers from the main roller before the main portion of the awning has reached its closed position of rest, said means being adapted to automatically connect said side rollers with 105 said main roller upon the initial downward movement of the main awning.

In witness whereof, I hereunto subscribe my name to this specification.

MARCO ANTHONY STELLA.
